Attorney

UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

ELECTRIC BLASTING CAP.

Original application filed July 22, 1925, Serial No. 45,327. Divided and this application filed December 7, 1925. Serial No. 73,638.

This invention has for its object to provide an electric blasting cap which cannot be prematurely exploded by accidentally, or otherwise, coming in contact with stray electric currents, of any nature, either while being transported or actually used on the job. This application is divisional to my pending application No. 45327.

Many cases have been recorded where loss of life and destruction of property have been caused by premature explosions of dynamite or other commercial explosives. There was a cause for each of these accidents. Cases are on record where a shot has been prepared for firing and which has prematurely exploded, apparently without cause. It is thus seen that the cause for premature explosions is not always visible to an observer. With the ever increasing use of electrical power and electric labor saving appliances in and about coal mines and quarries and construction projects, there is always the possibility of encountering stray electric currents. These currents may be found flowing through moist earth, between the source of supply and bad joints or bonds of trolley rails or on water or steam pipes. The average electric blasting cap of present American manufacture can be fired by impressing across the ends of its lead wires an E. M. F. of from one to two volts. Potentials of this order cannot be detected without the aid of electrical measuring instruments. Many tests have been made wherein considerably higher potentials have been recorded and yet could not be detected by moist hands of an observer. Not all of the premature explosions have been due to electric blasting caps being exploded by stray currents or accidental contact of same with conductors carrying electric current, but a number of accidents have thus been caused.

Among the objects of my invention is to provide an electrically insulated fuse head or igniting device for the electric blasting cap, in order that grounding of the lead wires or short circuiting of same by touching the side wall of the metal shell, will be prevented. This insulation will make it impossible to complete a circuit through the metal shell and either of the lead wires to which the fuse head is attached. The method of assembly of a safety electric blasting cap, hereinafter described, with the method of application, differs from the char-

acter of that shown in U. S. Patent 720,073 issued to Schmidt and Kraunischfeldt and my former U. S. Patent 1,354,100 in that it is not intended to insulate and mechanically support or prevent separation of the lead wires; this now being accomplished by a metal fuse head covered by U. S. Patent 1,407,167 issued to Charles C. Jessen.

A further object is to provide a fuse head for an electric blasting cap, insulated from the charge in the base of the shell and from the side wall of the metal shell and which can be used in connection with a safety shunt or some means of short circuiting the exposed ends of the lead wires. When this has been done the electric blasting cap cannot be exploded by the electric current so long as the safety shunt is in place. My new electric blasting cap differs in this respect from other types of electric blasting caps, except the match-head type, and differs from the former match-head type in that the efficiency of the insulation is not dependent upon special forms of assembly in the manufacture of the caps.

Further objects and advantages of the invention will be set forth in the detailed description which now follows:

In the accompanying drawing:

Fig. 1 is a vertical sectional view of an electrical detonator constructed in accordance with the invention, and

Fig. 2 is a view upon an enlarged scale of the electrical fuse head and its insulator.

Like numerals designate corresponding parts in both of the figures of the drawing.

It is common practice to utilize electrical fuse heads, comprising strips 5 and 6 of conductive material, which are held in separated relation by an insulating web 7 of cardboard, paper, or the like. The lead wires 8 and 9 are soldered or otherwise suitably connected at 10 and 11 to the strips 5 and 6, said lead wires being insulated, as indicated at 12 and 13. A suitable match-head composition 14 is ignited when current flows in the circuit constituted by wire 8, strip 5, strip 6 and wire 9, it being understood that the lower ends of the strips 5 and 6 are connected by an ignition filament (not shown) 105 which is embedded in the match-head composition.

In carrying out the present invention, I provide a spool-like body 15 of dielectric material, by which the ignition assembly is 110

held in centered relation within the shell 16 of the detonator. A rubber gasket 17 surrounds the spool-like body and constitutes a water-proof sealing element between the 5 spool and the inner wall of the shell. The explosive charge 18, which may be a body of mercury fulminate, is of such consistency as to maintain its form as the detonator is moved to varying positions. In this respect, 10 it differs from some detonators which employ loose powder. A cylindrical tube 19, which fits snugly within the shell 16, is so disposed that its lower end bears upon the charge 18 and its upper end is engaged by 15 the spool 15. In process of assembly, the match-head composition, and associated parts, are coated with a highly dielectric material, such, for example, as nitro-cellulose varnish. After the spool and its rubber 20 gasket have been forced downwardly into the shell 16, until the tube 19 is firmly bound between the lower end of the spool and the upper end of the charge 18, a body 25 of dielectric and water-proof sealing material 21 is poured into place and in order that this sealing material may be firmly engaged by the shell in such a way as to resist dislodgment therefrom, the shell is provided with an internal groove 23, into which 30 said sealing material enters.

In practice, I contemplate twisting the outer exposed ends of the lead wires into engagement with each other, directly at the point of termination of the insulation thereon, to thereby create a short circuit at such point of connection. This insures that accidental contact of the exposed ends of the lead wires with sources of stray electric currents will not result in the flow of current 10 through the fuse head assembly. The tube 19 further insulates the fuse head from the side walls of the metal shell.

An electric detonator constructed as herein shown and described cannot be exploded by 15 stray electric current nor can it be injuriously affected by moisture. Moisture cannot find its way into the detonator because of the presence of the gasket 17.

It is to be understood that the invention 20 is not limited to the precise construction set forth but that it includes within its purview whatever changes fairly come within either the terms or the spirit of the appended claims.

Having described my invention, what I 25 claim is:

1. An electric detonator comprising a shell, an explosive charge in the lower end

of said shell, an electrical fuse head assembly, a centering means for said fuse head assembly comprising a body of dielectric material fitted snugly within the shell and a tube of insulating material between the body of dielectric material and the charge and engaged by both of them and into the 60 open interior of which the lower end of the electrical fuse head assembly projects, the exposed portions of the fuse head assembly within the said open interior of the tube being coated with a dielectric material. 70

2. A device of the character described comprising a shell, an electrical fuse head assembly, a body of dielectric material of spool-like form through which the fuse head assembly projects and which body fits snugly 75 within the shell, a water-proof gasket surrounding said body and fitting snugly within the shell and a charge within the shell below the said body.

3. A structure as recited in claim 2 in 80 combination with an insulating tube fitting snugly within the shell and having its upper end engaged by the spool-like body and its lower end resting upon the charge and a body of sealing material within the shell, 85 outwardly of said spool-like body.

4. A unit for an electric detonator comprising an electrical fuse head assembly, a body of dielectric material of spool-like form through which said fuse head assembly 90 passes and a gasket of compressible, water-proof material extending about the circumference of said spool-like body.

5. A detonator comprising a shell, an explosive charge therein of permanent form, 95 a tube of insulating material fitting snugly within the shell and resting upon said charge, a fuse head assembly, a spool-like body of dielectric material through which said fuse head assembly passes, and a packing element surrounding the spool-like body and forming a water tight joint between the same and the wall of the shell, the lower end of said fuse head assembly projecting beyond said body and lying within said tube 105 and a body of sealing material within the shell, outwardly of the spool-like body and bearing upon said spool-like body.

6. A structure as recited in claim 5, in 110 combination with a compressible water-proof gasket surrounding the spool-like body and fitting snugly within said shell.

In testimony whereof he affixes his signature.

HARRY L. GRANT.
